WINDOW CONTROL DEVICE

Axel W. Anderberg and Thomas W. S. Reid, Los Angeles, and George A. Taylor, Glendale, Calif., assignors to A. W. Anderberg Manufacturing Co., Los Angeles, Calif., a corporation of California

Filed Aug. 26, 1957, Ser. No. 680,202

4 Claims. (Cl. 292—262)

This invention relates to window control devices, and included in the objects of this invention are:

First, to provide a device for the control of windows of the casement type which pivot outwardly about vertical or horizontal axes and which are mounted externally of the window screen, or for the control of similarly mounted external awnings, the window push bar being arranged to operate the window without disturbing the window screen.

Second, to provide a window control device which also functions as a latch to draw the window tightly against the window frame as the window is brought to its closed position, thus eliminating the need of a separate window latch.

Third, to provide a window control device which is adaptable to windows of various dimensions, and although especially suited for use with aluminum framed windows is also adaptable to wood framed windows.

Fourth, to provide a window control device which utilizes a novel, arcuately curved, extensible slide bar.

With the above and other objects in view, as may appear hereinafter, reference is directed to the accompanying drawings in which:

Figure 1 is a fragmentary sectional view taken through 1—1 of Fig. 2 showing a window frame, window sash, and screen with the window in its closed position and the window control device in its locking position;

Fig. 2 is a fragmentary elevational view of the window frame, window sash, and screen taken from the interior side thereof, and showing the window control device in its locking position;

Fig. 3 is an enlarged fragmentary sectional view through 3—3 of Fig. 1;

Fig. 4 is a fragmentary sectional view similar to Fig. 3, but showing the window control device adapted to a wooden window frame and window sash;

Fig. 5 is a perspective view of the sash bracket and link member viewed from the underside thereof.

Fig. 6 is an enlarged fragmentary sectional view through 6—6 of Fig. 1;

Fig. 7 is a sectional view taken substantially along the plane of Fig. 3, showing the window sash in its intermediate open position and portions of the window control device in side elevation;

Fig. 8 is a sectional view similar to Fig. 7, showing the window control device in its full extended position;

Fig. 9 is a sectional view taken substantially through 9—9 of Fig. 8, showing the window control device in plan.

The window control device is illustrated in Figs. 1 through 3 and 5 through 9 as adapted to a typical metal window structure.

A typical or conventional window structure includes a metal window frame 1 formed of extruded metal so as to define an interior, inwardly directed lip 2 connected by a web 3 to an exterior, outwardly directed lip 4.

2

The window frame is intended to be mounted within a window opening.

Fitted within the window frame 1 is a window sash 5 which is likewise provided with an interior inwardly directed lip 6 connected by a web 7 to an exterior, outwardly directed lip 8. The lips of the window sash 5 bear against the lips of the window frame 1 when the window sash is in its closed position, such as shown in Figs. 1, 2, and 3. The window sash receives a window pane 9 which is held in place against the lip 6 by a retainer member 10.

The window sash 5 is pivotably connected to the window frame by various hinges or mounting devices, not shown. One such type of mounting device is shown in Patent No. 2,784,459, issued March 12, 1957. The window sash may be mounted so as to pivot about a horizontal axis or about a vertical axis, in which case the window control device is mounted at the top or bottom of the window, or at the side thereof, as the case may be.

It is customary to mount on the interior side of the window frame 1 a window screen sash 11 containing a window screen 12. The window screen sash is in the form of a thin metal frame which overlaps the margin 25 of the lip 2.

The window control device includes a sash bracket 13 which is secured to the window sash 5 at one side thereof between the web 7 and the corresponding outwardly directed lip 8 so that when the window sash is 30 in its closed position the sash bracket 13 is disposed between the web 7 and the web 3.

The sash bracket 13 includes a pair of right angularly disposed flanges 14 and 15, confronting, respectively, the web 7 and lip 8. One or both of these flanges may be 35 secured by means of rivets or screws. The sash bracket 13 is divided lengthwise by partitions 16 having slots 17 therein which slidably receive a cross bar 18.

The cross bar 18 is secured to or journals a link member 19, which extends outwardly from the sash bracket 40 13. The cross bar permits pivotal movement of the link member about an axis parallel to the side of the window sash 5 on which the sash bracket is mounted as well as limited sliding movement.

The ends of the partitions 16 remote from the flange 45 15 are joined to partial walls 20 which in turn are joined to partial partitions 21 directed toward the flanges 15 parallel to the partitions 16. The partitions 16, walls 20, and partial partitions 21 form housings or pockets 50 for compression springs 22 anchored to the extended ends 55 of the cross bar 18 so as to urge the cross bar and link member 19 toward the flange 15, that is, toward its retracted position.

The extended end of the link member 19 is divided to 55 form a yoke 23 which is provided with a journal rivet 24 defining an axis at right angles to the cross bar 18. The yoke 23 receives a push bar 25 which is journaled by the rivet 24. The push bar 25 is in the form of an arcuate strap and is slidably received in a push sleeve 26 which is also arcuately curved.

The push bar 25 is provided near its end remote from the yoke 23 with a push button 27 backed by a leaf spring 28 and arranged to enter a perforation 29 provided in the push sleeve 26. In the construction shown, a perforation 29 is provided near each end of the push sleeve 26 so that the push bar 25 may be latched in a telescoped or retracted position relative to the push sleeve, as shown in Figs. 1, 2, and 7, or in an extended position relative to the push sleeve 26, as shown in Figs. 8 and 9. The extended end of the push sleeve 26 is provided with a handle 30 which may terminate in a finger loop.

One side of the inwardly directed lip 2 of the window frame 1 is provided with an aperture in alignment with

the sash bracket 13 over which is mounted a guide bracket 31. The guide bracket is provided with lateral ears which receive screws for attachment to the window frame. The guide bracket may have a projection 32 which fits within and lines the aperture.

The guide bracket 31 is provided with a rectangular slot 33 which slidably receives the push sleeve 26 and push bar 25. The interior end of the slot 33, that is, the end remote from the projection 32, is preferably flared as indicated by 34.

The link member 19 has sufficient length that when the window sash 5 occupies its closed position, such as shown in Figs. 1, 2, and 3, the push bar 25 and push sleeve 26 may be pivoted about the axis of the journal rivet 24, so that the push bar may be forced to a position parallel with the window frame 1 by fulcruming the push bar 25 over a margin 35 of the guide bracket 31. This action draws the window sash inwardly against the window frame, against the compression of the springs 22.

A latching bracket 36 is provided at one side of the guide bracket 31 and is provided with a hook end 37 which retains the push sleeve 26 in its laterally extending or locking position.

Operation of the window control device is as follows:

When it is desired to open the window sash 5 from the position shown in Figs. 1, 2, and 3, the push sleeve 26 is first depressed slightly to disengage the hook end 37 of the latching bracket 36, and then rotated about the pivotal axis of the push bar 25 in alignment with the link member 19. The push bar and push sleeve are then pushed outwardly through the guide bracket 31 so as to swing the window sash 5 toward the position shown in Fig. 7.

The extremity of the push sleeve 26 forms a shoulder 38 which engages the margin of the slot 33 so as to hold the window sash extended. If it is desired to extend the window sash further, the button 27 is initially depressed and the push sleeve pulled outwardly relative to the push bar 25 until the button engages the other perforation, whereupon the push bar and push sleeve are forced through the slot 33, pivoting the window sash to the position such as shown in Figs. 8 and 9. In this case, also, the shoulder 38 engages the slot 33 to hold the window sash in its extended position.

To retract the window sash 5 it is merely necessary to disengage the shoulder 38 from the margin of the slot 33 and pull the push sleeve 26 inwardly. When the window sash reaches its closed position the push sleeve is then displaced angularly relative to the link member 19. When the push sleeve 26 is in its extended position, the button 27 is depressed to permit telescoping of the push sleeve 26 over the push bar 25 are pivoted to the position shown in Figs. 1, 2, and 3, causing the push bar 25 to fulcrum over the margin 35 of the guide bracket 31 and draw link member 19 in opposition to the springs 22 whereby the compressive force of the springs urges the window sash 5 into a snug sealing engagement with the window frame 1.

Reference is now directed to Fig. 4. This construction is essentially the same as the previously described structure. However, the guide bracket 31a may be modified so as to be secured to the top of a wooden sill 39, and the wooden window sash designated 40 may be provided with a recess or pocket to receive the sash bracket 13. The operation of the window control device as installed on a wooden window frame and window sash is identical to the operation of the control device as mounted on a metal window frame and window sash.

It is sometimes desirable, in order to facilitate cleaning of the window, that control device be disconnected and permit movement unrestrained by the control device. This can be readily done by depressing the push button and completely withdrawing the push sleeve from the push bar.

It will be observed that the push bar 25 may be pivoted

in either direction relative to the guide bracket 31 for either "left" or "right" mounting of the window control device.

While particular embodiments of this invention have been shown and described, it is not intended to limit the same to the exact details of the constructions set forth, and it embraces such changes, modifications, and equivalents of the parts and their formation and arrangement as come within the purview of the appended claims.

10. What is claimed is:

1. A window control device for use in a window having a window frame and a pivotable window sash, comprising: a bracket adapted to be attached to said window sash; a link member; connecting means pivotably and slidably connecting said link member to said bracket about an axis parallel with a side of said window sash; yieldable means urging said link member toward a retracted position relative to said bracket; a push bar structure pivotably connected to said link member about a second axis perpendicular to the pivotal axis of said connecting means; a guide member mounted on said window frame and having a guide aperture to slidably receive said push bar structure and having means cooperating with said push bar structure to hold said push bar structure in an extended position thereby to hold said window sash in an open position; said guide member also arranged to slidably receive said link member and to cooperate with said push bar structure on movement thereof about said second pivotal axis to extend said link member in opposition to said yieldable means and to draw said window sash against said window frame thereby to lock said window sash in a closed position.

2. A window control device for use in a window having a window frame and a pivotable window sash, comprising: a bracket adapted to be attached to said window sash; a link member; connecting means pivotably and slidably connecting said link member to said bracket about an axis parallel with a side of said window sash; yieldable means urging said link member toward a retracted position relative to said bracket; a push bar structure pivotably connected to said link member about a second axis perpendicular to the pivotal axis of said connecting means; said push bar structure including a pair of relatively telescoping arcuate push bar members and releasable means for interlocking said push bar members in relatively retracted and extended positions; a guide member mounted on said window frame and having a guide aperture to slidably receive said push bar structure; one of said push bar members having a shoulder engageable with a margin of said guide aperture to dispose said push bar member in an extended position, said other push bar member being extensible therefrom to hold said window in various open positions; said guide member also arranged to slidably receive said link member and to cooperate with said push bar structure on movement thereof about said second pivotal axis to extend said link member in opposition to said yieldable means and to draw said window sash against said window frame thereby to lock said window sash in a closed position.

3. A window control device for use in a window having a window frame and a pivotable window sash, comprising: a bracket adapted for attachment to said window sash; a link member; means connecting said link member to said bracket; said means including a yieldable element tending to retract said link member relative to said sash; a push bar pivotably connected to said link member; a guide member mounted on said window frame for slidably receiving said push bar for opening and closing said window sash relative to said window frame, and also receiving said link member as said window sash approaches its closed position; fulcrum means engageable with said push bar on pivoting of said push bar as said window sash approaches its closed position, to draw said link member against the action of said yieldable element thereby to draw said window sash tightly against said window frame.

4. A window control device for use in a window having a window frame and a pivotable window sash, comprising: a bracket adapted to be attached to said sash; a link bar pivotally connected with said bracket about a first axis parallel with the pivotal axis of said sash, and having limited longitudinal movement along a second axis perpendicular to said pivotal axis between an extended and retracted position; yieldable means urging said link bar toward its retracted position; a push bar means pivotally connected to said link bar about a third axis perpendicular to said first and second axes; and guide means for said push bar means and link bar mounted on said frame, and including fulcrum means cooperating with the pivotal connection between said push bar means and said

link bar to extend said link bar along said second axis and draw said sash toward said frame.
